LEWIS GOULDING, OF MEDFIELD, ASSIGNOR TO HIMSELF AND JAMES E. CARPENTER, OF FOXBOROUGH, MASSACHUSETTS.

Letters Patent No. 72,021, dated December 10, 1867.

IMPROVED KNIFE-CLEANER.

The Schedule referred to in these Letters Patent and making part of the same.

TO ALL WHOM IT MAY CONCERN:

Be it known that I, LEWIS GOULDING, of Medfield, in the county of Norfolk, and State of Massachusetts, have invented an Improved Implement for Scouring or Cleaning Knives, &c.; and do hereby declare the following to be a full, clear, and exact description thereof, reference being had to the accompanying drawings, in which—

Figure 1 is a perspective view,

Figure 2 a vertical and longitudinal section, and

Figure 3 a transverse section of such implement.

The end sought in making this invention is to lessen the disagreeable labor of scouring knives or forks, as by its employment this may be accomplished in less time, and with the expenditure of much less strength, than by the old mode.

The invention consists in applying to a rectangular board or shallow box, a bar or lever, provided with a rubbing or scouring-pad, and a projecting handle for ease in operating it, substantially as hereinafter explained.

In the accompanying drawings illustrating my invention, A denotes a rectangular board or tablet, having an enclosing ledge, a, to confine and prevent escape of dirt or the polishing-material used in scouring. A small enclosure or sunken space, b, is formed in one corner of the board, for receiving the scouring-powder or paste, and there may also be an inclined bed, c, applied to the surface of the board, and between its outer edge and the enclosure b, for supporting the knife or other utensil to be cleaned. To the extreme opposite end of the board A, a bar, B, is pivoted at one end, as shown at d in the drawings, the said bar extending over and across the surface of the board, and having formed upon its outer end a handle, e, which projects beyond the board a sufficient distance to enable it to be readily grasped by a person's hand. A longitudinal slot, f, is made through the bar B, and over the bed c before referred to, the object of this slot being to receive the scouring-pad or rubber g, which in this instance is composed of a number of pieces of leather of equal size, placed side by side, and inserted within the slot, and secured in place by clamp-screws i, screwed through one side of the bar and against such pad. If considered preferable, the screws may pass entirely through the pad, and into the opposite side of the bar. The pad may be made of cork, wood, or any suitable material. The mode of pivoting the bar B to the board A, should be such as to allow the necessary backward and forward movements of it over the knife, and at the same time all on it to be raised sufficiently high to receive between it and the bed c, a knife, placed on edge in order to scour its back.

Previous to using the above-described implement, it is to be securely clamped to the upper surface of a table, or to any other suitable place.

In operating with it, the knife is to be seized by its handle with the left hand, and its blade laid flatwise upon the bed c. The handle of the bar B is next to be grasped in the right hand, and its pad or rubber dipped into the enclosure b, which has previously been supplied with the scouring-material or paste, a portion of which will adhere to it. The bar B is now to be moved over upon the knife, and with the pad in contact with the blade, and moved briskly back and forth thereon, until such blade is sufficiently scoured, the pad being dipped from time to time within the scouring-material, as occasion may require. A fork may be scoured with my invention, with the same facility as a knife. As the scouring-pad becomes worn, its confining-screws may be loosened, which allows it to be lowered to the desired extent, and the screws subsequently tightened.

The advantages resulting from the use of the implement, made as above explained, are first, as a leverage (varying in power with the length of the handle) is exerted upon the rubber or scouring-pad, the manual exertion required is very much reduced, this being in addition to the ease with which the handle may be retained within the hand, in comparison to the old mode of holding a cork between the thumb and finger; second, the back of the knife and edges of the tines of a fork, as well as the bolsters of both, may readily be scoured by means of my invention, the inability to accomplish which has been urged as an objection to most if not all machines now in use.

The implement is compact in form, and combines or contains within itself all the requisites for performing the desired result. The bar B with its pad may be used separately from the rest of the device, and applied to an ordinary table or bench, for the purpose of polishing metals or other substances.

1. I claim the combination, in an implement for scouring knives, of the bar B with its adjustable pad g, arranged for operation as and for the purposes herein shown and described.
2. I claim, in combination with the board or tablet A, the bar B provided with the scouring-pad g, and pivoted to such board, and operating with its upper surface, or upon an inclined bed formed thereon, essentially as herein set forth and explained.
3. I claim the combination, with the bar B and its pad, of the knife-bed and the enclosure for holding and receiving the scouring-material, arranged relatively to each other and to the bar B as herein shown and set forth.

LEWIS GOULDING.
